US0D1060475S

(12) **United States Design Patent** (10) **Patent No.:** **US D1,060,475 S**
(45) **Date of Patent:** **** Feb. 4, 2025**

(54) **HOUSING**

(71) Applicant: **QUOYI INNOVATIVE PRODUCTS, INC.**, Austin, TX (US)

(72) Inventor: **Richard B. Gorelick**, Austin, TX (US)

(73) Assignee: **QUOYI INNOVATIVE PRODUCTS, INC.**, Austin, TX (US)

(**) Term: **15 Years**

(21) Appl. No.: **29/897,440**

(22) Filed: **Jul. 14, 2023**

(51) **LOC (15) Cl.** **16-01**

(52) **U.S. Cl.**

USPC **D16/219**

(58) **Field of Classification Search**

USPC D16/136, 206, 211, 216-220, 237; D14/195, 203.6, 228, 506, 509; D10/46, D10/104, 1, 106.5, 114.6, 114.8, 132; D8/66, 310, 350, 352, 396

CPC G03B 11/00; G03B 11/04; G03B 11/043; G03B 17/56; H04N 23/55

(57) **CLAIM**

The ornamental design for a housing as shown and described.

DESCRIPTION

FIG. 1 is a front, right, top perspective view of a housing showing my new design.

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The dashed-dot lines form the boundary of the claimed design and the even dashed broken lines shown in the drawings are included for the purpose of illustrating portions of the housing that form no part of the claimed design.

1 Claim, 7 Drawing Sheets
